W. Stueckle

Attorney

UNITED STATES PATENT OFFICE.

DAVID ROBERT YARNALL, OF PHILADELPHIA, PENNSYLVANIA, ASSIGNOR TO YARNALL-WARING COMPANY, OF PHILADELPHIA, PENNSYLVANIA, A CORPORATION OF PENNSYLVANIA.

INDICATING AND RECORDING NONRETURN VALVE.

Application filed April 10, 1924. Serial No. 705,473.

My invention relates to valves known as non-return valves which are located between individual boilers and the headers or manifolds into which the boilers discharge and 5 from which steam distribution is had.

The main purpose of my invention is to indicate the position of a non-return valve.

A further purpose of my invention is to utilize the non-return valves as flow meters 10 for measuring actually as well as comparatively the performance of the individual boilers.

Further purposes will appear in the specification and in the claim.

15 I have preferred to illustrate my invention by but two forms varied for the purpose only of suiting different types of valves, both forms of which are practical, efficient and inexpensive and which at the same time 20 well illustrate the principles of my invention.

Figure 1 is a vertical section through a non-return valve of the angle type showing recording connections, the section being on 25 line 1—1 of Figure 2.

Figure 2 is a section of Figure 1 taken upon line 2—2.

Figure 3 is a section of the invention applied to a globe type of valve.

30 In the drawings similar numerals indicate like parts.

Describing in illustration and not in limitation and referring to the drawings:—

As is well known, non-return valves may 35 be closed positively against flow of steam from the individual boilers to the header or manifold but cannot be opened positively, depending for their opening upon an excess of pressure upon the valve element from 40 the side of the individual boiler as compared with the pressure upon the upper side of the valve from the header. No means has been provided prior to my invention for determining the position of the valve except 45 as its extent of possible opening could be limited and as it could be held closed.

It has been customary in many plants to use flow meters in series with the non-return valves, one in each connection, between 50 each boiler and the header.

Dependence has been placed upon the flow meters to determine the performance of the individual boilers both comparatively and

quantitatively. My invention is intended by indicating and preferably recording the position of the movable element to roughly show the flow of steam through the non-return valve, and to determine the performance of the boilers by the position of the non-return valves. This not only gives 55 comparative performance of the different boilers but provides measure of flow of steam with a fair degree of accuracy.

Describing the form shown in Figure 1, a non-return valve is illustrated in which the body 5 has inlet 6 from the boiler and outlet 7 to the manifold. A removable valve seat is shown at 8 and the valve element 9 is connected with a cupped piston 10 by stem 11. The piston floats and loosely 60 travels within cylinder 12 and is supplied with steam through its loose fit in the cylinder or/and through any small port 13.

The cylinder depends from a cover plate 14 upon which is supported a yoke 15 65 threaded in its outer end 16. Within the threaded end is secured a controlling stem 17 which bears at its bottom 18 against the cup and which passes through a gland 19.

The valve and stem are guided at their lower end by a pin 20 passing through a guide 21 within any suitable spider 22.

As thus far described the non-return valve is not intended to differ from other non-return valves in which the steam will pass 85 through the valve freely from the boiler when the pressure of the boiler is above that of the header but the valve will close automatically by weight when the pressure in the boiler falls and will close suddenly with 90 any sudden flow of steam from the manifold toward the boiler. The valve can be limited in its opening or can be positively closed as shown in Figure 1 by screwing down the stem 17 as by handle 23.

For the purpose of indicating and desirably recording the position of the non-return valve, using the indication or record with a calibration curve or chart to obtain meter readings I provide operating connection between a movable part of the valve and an indicating and preferably recording member outside of the valve casing. As shown in Figure 1 this connection conveniently engages the neck of the valve.

100 Here the arm 24 is yoked at the end as

at 25 and is provided with pins 26 retained in position by nuts 27 so as to project within the groove 28. The arm is pivoted at 30 to swing upwardly and downwardly with 5 movement of the floating valve.

The outer end of the arm 24 carries a sleeve 29 which is secured to swing with a shaft 30 passing through the wall of the casing and protected from steam leakage 10 by packing 31, held in place by a gland 32. The shaft has bearing at its inner end 33 and at its outer end as preferred against the metal of the valve as at 34 or in the gland 32.

15 The mounting of the mechanism is facilitated by providing a compartment opposite the stem which compartment is shown as having side walls 35, 36 and end wall 37. The sleeve preferably fits between finished 20 faces 38, 39 within the side walls, so as to prevent end movement. The shaft is kept in place by a set screw 40 passing through the sleeve and impinging against the shaft.

This construction is readily assembled by 25 insertion of the shaft through the sleeve in position and fastening the set screw before the cover 14 is applied and canting or lateral movement of the valve may be given to engage the pins 26 within the groove 28 in 30 the stem.

Upon the projecting outer end of the shaft 30, I mount an arm 41 which is effective as an indicator by reason of its position and which also carries a recording pen 42 and 35 ink holder 43 by which record is made upon the chart 44 carried by a rotor recording drum 45. The standard for this drum is indicated at 46 and is intended to carry the usual mechanism for rotating the drum. 40 Since this is well known in the recording art and need not be of any special construction but can be of standard stock, it has not been deemed necessary to illustrate it further than as indicated including the winding 45 stem 47.

The recording drum is supported upon a bracket 48 preferably mounted upon the valve so as to make the unit self-contained.

In Figure 3 the non-return valve is in-

tended to be of the same character except 50 that it is applied to a globe valve 5' and so the indicating recording arm forms an extension 20² of the guiding stem 20', instead of being connected to swing about a center.

Because of the shape of the globe valve 55 the extended stem passes directly through the bottom of the valve body where it is protected against leakage by packing 31' and gland 32'. In this case the pens 42 and ink holder 43 are carried by a bracket 49 secured to and movable directly with the extended stem 20². The record drum 45 is shown as supported from a bracket 48' secured to the flange 50 of the valve or from any fixed bracket 51 or by means of both of 60 these supports as desired, the manner of support being immaterial.

It will be noted that the movement of the pen in Figure 3 is the same as that of the 70 valve.

In either type of valve shown, adaptation as a meter depends upon the movable valve element floating in the stream of steam, pressed toward closure by weight of the movable elements while pressed open 75 with an equal force by the flowing steam.

Friction which limits the responsiveness of indications to small variations in flow is materially diminished by the mechanical vibration normally present at these valves. 80

As variations and changes in the application of my invention will occur to others skilled in the art, reading my disclosure and in view of their own whims and preferences, it is my intention to cover herein all such 85 modifications and changes as come within the reasonable spirit and scope of my claim.

Having thus described my invention, what I claim as new and desire to secure by Letters Patent is:—

A non-return stop and check valve of the globe type having a damper upon the valve, in combination with a valve stem therefrom passing through the body of the valve, packing therefor and recording connections 95 mounted upon the said stem.

DAVID ROBERT YARNALL.
